UNITED STATES PATENT OFFICE.

THOMAS E. MURRAY, JR., AND JOSEPH B. MURRAY, OF BROOKLYN, NEW YORK.

METHOD OF ATTACHING FUSE-TUBES TO HAND-GRENADES OF THIN METAL.

1,286,062.

Specification of Letters Patent. Patented Nov. 26, 1918.

Application filed July 15, 1918. Serial No. 244,936.

To all whom it may concern:

Be it known that we, THOMAS E. MURRAY, Jr., and JOSEPH B. MURRAY, citizens of the United States, residing at Brooklyn, in the county of Kings and State of New York, have invented a certain new and useful Improvement in Methods of Attaching Fuse-Tubes to Hand-Grenades of Thin Metal, of which the following is a specification.

10 The invention is a method of attaching a fuse tube to a hand grenade of thin metal, so as to make an integral joint between said parts and to avoid the burning of said metal.

15 In the accompanying drawings—

Figure 1 is an elevation of the completed grenade. Fig. 2 shows the grenade in elevation and the tube in vertical section; a part of the grenade is broken away and in section. The grenade and tube are shown seated in recesses in the welding electrodes, and the parts in the position before welding. Fig. 3 is a view similar to Fig. 2, showing the parts in the position after welding.

20 25 30 35 Similar letters of reference indicate like parts.

The grenade is formed in two cup-shaped sections A, B of thin metal. Section A is flattened, and has an opening C surrounded by an outwardly turned flange D. The two sections are placed with their edges in registry and are united by electric welding. The fuse tube E is made of heavier metal, and has an annular flange F at one end which is thicker than the body portion of said fuse tube. The grenade is placed in a recess G of an electrode H. The tube is

seated in a correspondingly formed recess in an electrode I, with its outer face bearing upon flange D, as shown in Fig. 2. The 40 welding current being established, electrode I is moved downwardly to press the flange F upon the flange D. Flange D becomes fused and disappears, the melted metal thereof serving to unite the tube and section 45 A together. The enlarged flange E affords a body of metal which absorbs sufficient of the heat to prevent the thin metal of section A, outside of the flange D, from being burned. We preferably make the flange E 50 polygonal in form, so that a wrench may be applied thereto to hold the grenade during loading and insertion of the fuse.

We claim:

55 The method of uniting a fuse tube to a hand grenade of thin metal, which consists in forming in a flattened end of said grenade an opening surrounded by an outwardly turned flange, forming a fuse tube having at one end a surrounding flange of metal 60 thicker than the body portion of said tube, placing the face of said tube flange upon said grenade flange, pressing said flanges together, and establishing a welding current through them; whereby said grenade flange 65 becomes fused and the said tube flange united to the flattened end of said grenade.

In testimony whereof we have affixed our signatures in presence of two witnesses.

THOMAS E. MURRAY, JR.
JOSEPH B. MURRAY.
